UNITED STATES PATENT OFFICE.

JOSIPH KOSMERL, OF COLLINWOOD, OHIO.

REVOLVING REFRIGERATOR.

1,282,241.

Specification of Letters Patent.

Patented Oct. 22, 1918.

Application filed January 19, 1918. Serial No. 212,636.

To all whom it may concern:

Be it known that I, JOSEPH KOSMERL, citizen of the United States, residing at Collinwood, in the county of Cuyahoga and State of Ohio, have invented certain new and useful Improvements in Revolving Refrigerators, of which the following is a specification.

This invention relates to certain new and useful improvements in revolving refrigerators.

The primary object of the invention is the provision of a refrigerator especially adapted for household use arranged to readily revolve for gaining access to different portions thereof, suitable closures being arranged for the sides and top of the structure.

A further object of the invention is the provision of a revolving refrigerator having a cooling means for more evenly lowering the temperature of the food chamber and at the same time providing a serviceable drain for the ice-chamber.

25 A still further object of the invention is the provision of a revolving refrigerator having food chambers readily accessible from all sides thereof, the device being provided with top, bottom and central cooling members adapted for maintaining a substantially uniform low temperature throughout the food chambers.

In the drawings forming part of this application and in which like reference characters designate corresponding parts throughout the several views:

Figure 1 is a central vertical longitudinal sectional view of the device taken upon lines 3—3 of Figs. 3, 5 and 6;

40 Fig. 2 is a side elevation of the device partially broken away upon lines 4—4 of Fig. 3;

Fig. 3 is a top plan view of the device;

Fig. 4 is a top plan view of one of the tray forms detached;

Fig. 5 is a horizontal transverse sectional view of the device taken upon line 1—1 of Fig. 1;

Fig. 6 is a similar sectional view taken upon line 2—2 of Fig. 1;

Fig. 7 is a side view of a portion of the drain; and

Fig. 8 is a top plan view of a portion of the base member and plate.

55 Referring more in detail to the drawings, my refrigerator comprises a metallic cas-

ing *b*, hexagonal in cross section having a glass door *H* provided at each side thereof for gaining access to the interior of the casing. A tube *B'* is axially secured through the casing *b* extending through the top *N* and a bottom *b'* thereof. A block or bracket *E* is secured beneath the casing *b* to the tube *B'* and is mounted to revolve upon a plate *F* at the top of a suitable base *G*. Annular 65 ribs *S* are provided upon the plate *F* engaging within corresponding grooves in the lower face of the block *E*. A post *C* extends through the tube *B'* and is secured to the base *G* and plate *F* by means of a lock-nut *J* and in this manner, the casing *b* is revolvably mounted for gaining access to the interior thereof through any of the doors *H*.

An ice-chamber *P* is arranged in the upper portion of the device having a bottom *A'*, side *A''* and hinged top portions or doors *A'* and *A''*. A foraminous tray *b''* is arranged within the ice-compartment *P* upon which the ice may rest. A bottom lining *b''* and a side lining *b''* are provided for the ice-chest *P* while the opposite sides of the top of the ice-chest are provided with linings *b''* and *b''*.

The lid or cover *A''* has a metallic outer 85 covering *b''* while the lid *A'* has a metal outer covering *b''*.

A drain pipe *B* surrounds the tube *B'*, suitably spaced therefrom and connected at its upper end to the bottom lining *b''* constituting a drainage passage for the ice-chest *P*. A drain tank *O* is arranged at the bottom of the device with the lower end of the pipe *B* extending into the same and provided with perforations *M*. The tank *O* is arranged with a bottom *A'*, sides *A''* and a top *A''*, one side of the top being in the form of a door or lid *A'*. The tank *O* is suitably lined having a metallic bottom lining *b''*, side linings *b''* and top linings *b''*. 100 A metal frame *A* is arranged between the tank bottom *A'* and the bottom *b'* of the casing *b*. An outlet pipe *T* is provided for the tank *O* having a faucet *K*.

Angular iron braces *a'* are provided with in the casing at the corner portions thereof to which are attached brackets *d*. Collars *D* are secured upon the pipe *B* and tray frames or supports *a'', a''*, and *a''* are mounted upon the said collars *D* and brackets *d*. 110 Foraminous members or screens *c* are arranged upon the said frames, thereby form-

ing horizontal partitions and providing annular food-containing compartments or chambers R.

A stop I is carried by the top of the post 5 C adapted to be engaged by either lid A⁷ or A⁸ when opened while handles X' are provided for the said lids. It will be understood that upon opening either of the lids A⁷ or A⁸, ice may be deposited within the 10 chamber P upon the tray b¹², and during the melting of the ice, the water will drip through a central strainer M' at the top of the pipe B and pass through the pipe into the tank O at the bottom of the device. The 15 lid A⁴ of the tank O is watertight so that the cold water from the ice may fill the tank O as well as the pipe B to substantially the level of the strainer M', and whereby a body of cold water will be arranged at the bottom 20 ton of the refrigerator while a column of cold water will be provided centrally therethrough with the ice-chest P at the top of the device. The annular food chambers R will be maintained in a cold state by reason 25 of the ice P' within the top chamber P and the ice-water K within the pipe B and tank O. Access may be had to the food chambers by opening any of the doors H while the entire casing b is readily revolved upon the 30 post C. The tray members c being foraminous permit a circulation of the cooled air within the food chambers R, it being under-

stood that any articles to be kept cool may be placed upon the trays c. The positioning of the ribs S of the plate F within the 35 grooves V of the block E journals the lower end of the refrigerator upon the supporting base G while the arrangement of the upper end of the post C through a central perforation W in the refrigerator top N forms 40 an advantageous mounting for the refrigerator. A serviceable refrigerator is arranged which is convenient for household use and is adapted to utilize the ice to the greatest possible extent in affording refrigeration for the food compartments of the device.

What I claim as new is:

A refrigerator comprising an upright casing having hinged lids in the top thereof, 50 a tube axially secured in said casing, a block secured to the bottom of the casing and the lower end of the tube and having annular grooves in its lower face concentric with said tube, a supporting base, a bearing plate 55 centrally mounted upon said base having annular ribs arranged within said grooves, a journaling post secured upright upon said base and extending through the block, plate, tube and top of the casing, and a stop for 60 said lids secured on the upper end of said post.

In testimony whereof I affix my signature.

JOSIPH KOSMERL.
